(57) **CLAIM**

The ornamental design for a carpal tunnel wrist support, as shown and described.

DESCRIPTION

FIG. 1 is a perspective view of a carpal tunnel wrist support, showing new design;

FIG. 2 is a top view thereof;

FIG. 3 is a bottom view thereof;

FIG. 4 is a right side view thereof;

FIG. 5 is a left side view thereof;

FIG. 6 is a back view thereof; and,

FIG. 7 is a front view thereof.

The dotted lines are for illustrative purposes only and form no part of the claimed design.
